(57) **CLAIM**

The ornamental design for a vehicle side skirt, as shown and described.

DESCRIPTION

FIG. 1 is a perspective view of a vehicle side skirt.

FIG. 2 is a front elevational view of the vehicle side skirt of FIG. 1.

FIG. 3 is a back elevational view of the vehicle side skirt of FIG. 1.

FIG. 4 is a left side elevational view of the vehicle side skirt of FIG. 1.

FIG. 5 is a right side elevational view of the vehicle side skirt of FIG. 1.

FIG. 6 is a top plan view of the vehicle side skirt of FIG. 1.

FIG. 7 is a bottom plan view of the vehicle side skirt of FIG. 1; and,

FIG. 8 is a perspective view of the vehicle side skirt of FIG. 1 as part of a semi-truck cab.

The items shown with broken lines form no part of the claimed design.

1 Claim, 5 Drawing Sheets
